UNITED STATES PATENT OFFICE.

BENO J. GUNDLACH, OF BELLEVILLE, ILLINOIS.

CUTTING-MACHINE.

1,119,506.

Specification of Letters Patent.

Patented Dec. 1, 1914.

Application filed May 4, 1914. Serial No. 836,262.

To all whom it may concern:

Be it known that I, BENO J. GUNDLACH, a citizen of the United States, residing at Belleville, Illinois, have invented a certain 5 new and useful Improvement in Cutting-Machines, of which the following is a full, clear, and exact description, such as will enable others skilled in the art to which it appertains to make and use the same.

10 This invention relates to cutting machines, and has for its main object to provide a manually operated machine that will successfully cut asbestos shingles, which is small and compact enough to enable it to be carried around by a workman who is 15 shingling a roof, and which can be manufactured and sold at a low enough price to enable a carpenter or similar workman to purchase one for his individual use.

20 Another object is to provide a machine of the character described that will cut an asbestos shingle clean and even and also puncture holes in shingles; and still another is to provide an efficient hand-operated cutting 25 machine that comprises only a few parts of simple design that are not apt to break or get out of adjustment when the machine is used to cut a hard and tough fibrous substance, such, for example, as asbestos 30 shingles which cannot be cut successfully with a saw, hand-shears or the portable machines that are now generally used for cutting light-weight sheet metal.

Other objects and desirable features of 35 my invention will be hereinafter pointed out.

Figure 1 of the drawings is a side elevational view of my improved machine showing the cutters open. Fig. 2 is a similar 40 view showing the cutters closed. Fig. 3 is a vertical transverse sectional view taken on the line 3—3 of Fig. 1. Fig. 4 is a vertical transverse sectional view taken on the line 4—4 of Fig. 2; and Fig. 5 is a vertical 45 transverse sectional view taken on the line 5—5 of Fig. 1.

Referring to the drawings which illustrate the preferred form of my invention, A and B designate two cutters or knife 50 blades that are disposed diametrically opposite each other, and which are provided with substantially V-shaped cutting edges that form cuts in both faces, or sides of the sheet being operated on when the cutters 55 are closed or brought together. The cutter A, which I will term the stationary cutter,

is mounted in the upper edge of a stationary cutter holder 1, that consists of a long, rigid bar, and the cutter B, which I will term the movable cutter, is mounted in the 60 lower edge of a movable cutter holder 2 that is arranged directly above the stationary cutter holder 1. Said cutter holders are held in vertical alinement with each other by two pairs of vertically disposed guides 65 3 secured to the opposite end portions of the stationary holder 1 and embracing the movable holder 2. I also prefer to provide one of the cutter holders with auxiliary guide pins 4 that project from one edge of 70 same and enter the holes 5 in the edge of the other cutter holder, as shown in Fig. 5, said guide pins being long enough so that they will not be completely withdrawn from the holes 5 when the cutters are open or separated. The movable cutter is normally held in its elevated position by means of coil springs 6 that surround the guide pins 4, and which are arranged between the cutter holders adjacent the ends of same. The 75 movable cutter holder 2 is provided with stops or abutments 7 that are arranged between the vertically disposed guides 3 at each end of the machine, and thus prevent the movable cutter holder 2 from moving 80 longitudinally of the stationary cutter holder, said abutments 7 preferably consisting of pins that pass transversely through the cutter holder 2, as shown in 85 Figs. 3 and 4.

90 The actuating mechanism for the movable cutter consists of two levers 8 and 9 pivotally connected at 10 to the upper ends of the vertically disposed guides 3 and provided at their lower ends with cams 11 that bear 95 against the upper edge of the movable cutter holder 2 and force it downwardly when said levers are swung in one direction, as shown in Fig. 2. The movement of said levers in the opposite direction shifts the cams 100 11 into such a position that the springs 6 can raise the holder 2 and thus separate the cutters. The lever 8 is provided with an operating handle 8^a, and movement is transmitted from said lever to the lever 9 by means of 105 links 12 that are pivotally connected to said levers in such a manner that the cams 11 will exert uniform downward pressure on the movable cutter holder 2 when the handle 8^a is actuated in one direction.

110 The machine is provided with a base or legs that hold the knife holders in an up-

right position, and in the form of my invention herein shown said legs are formed by flanges 3^a on the lower ends of the bars that constitute the vertically disposed guides 5. The cutters A and B fit snugly in grooves that extend longitudinally of the cutter holders, and if desired, pins 13 can be passed transversely through the holders and cutters, as shown in Figs. 3 and 4 so as to 10 secure the cutters to their holders. I also prefer to form notches in the end portions of the cutter holders, as shown in Figs. 1 and 2, so as to form seats 6^a for the spring 6. A work table 14 projects laterally from 15 one side of the stationary cutter holder 1, as shown in Figs. 3 and 4, so as to support the sheet that is being cut, and said work table is inclined upwardly slightly from its inner 20 toward its outer end so that the sheet α will rest upon the upper edge of the stationary cutter A and on the outer end portion of the work table, as shown in Fig. 3, and thus cause the movable cutter B to force the sheet downwardly onto the stationary cutter A; in 25 other words, the work table 14 is so designed that there is sufficient space between the underside of the sheet α and the top surface of the work table at a point adjacent to the cutters to permit the movable cutter to force 30 the sheet downwardly far enough to cause the sharp edge of the stationary cutter to sink into the underside of the sheet, thus forming cuts in both sides of the sheet α . A stop 15 is arranged at one end of the 35 work table so as to prevent the sheet α from slipping longitudinally off the work table after the sheet has been cut, this being a very desirable feature in a machine that is used for cutting shingles, owing to the fact that 40 the machine is generally used on the roof of a building and is arranged at such an angle that the portion of the shingle lying on the work table would slide longitudinally off of same after the shingle has been severed if 45 the work table were not provided with a stop or similar device 15. The vertically disposed guides 3 are preferably so designed that the upper ends of same form stops or 50 abutments 16 that coöperate with the links 12 so as to limit the movement of the movable cutter holder 2 in both directions, as clearly shown in Figs. 1 and 2. At one end of the machine is an inclined support 17 for holding a shingle in which it is desired to 55 punch a hole, said support being arranged in such a position that a punch 18 on the lever 9 will pass through the shingle on the support and enter a hole 18^a in said support when the cutters are closed, as shown in 60 Fig. 2.

A machine of the construction above described will successfully cut asbestos shingles and other fibrous sheet material that is hard and tough; the machine is small and compact enough to enable it to be carried around 65

a roof by a workman who is shingling the roof and the machine can be manufactured at a low enough cost to make it practicable for a workman to purchase one for his individual use. There is no danger of the cutters springing or spreading apart during the cutting operation, as would be apt to result with a portable machine of the type now generally used for cutting light-weight sheet metal in which the knives or cutters travel past each other and shear the material, and, as the machine comprises only a few substantial parts of simple design, there is little danger of the machine breaking or getting out of adjustment when it is in use. 7

Having thus described my invention, what I claim is:

1. A cutting machine comprising a stationary cutter holder and a movable cutter holder, that consist of long rigid bars arranged in vertical alinement with each other and provided in their meeting edges with cutters whose edges are disposed diametrically opposite each other, vertically disposed guides that embrace the movable cutter holder, levers pivotally connected to said guides and provided with cams that bear against the upper edge of the movable cutter holder when said levers are moved in one direction, links pivotally connected to said levers for transmitting movement from one lever to the other, means for preventing said movable cutter holder from moving longitudinally when it is depressed, the upper ends of said guides forming abutments or stops that coöperate with said links to limit the movement of the movable cutter holder in both directions, and means for holding said cutter holders in an upright position. 9

2. A cutting machine comprising a stationary cutter holder provided with a laterally projecting work table whose outer end is bent upwardly to form an abutment that guides the work, a cutter in said holder whose edge supports the sheet that is being operated on, a movable cutter holder provided with a cutter that is arranged directly above the stationary cutter, a manually operated actuating device that comprises cams which exert downward pressure on the opposite end portions of the movable cutter holder, resilient means for elevating the movable cutter holder and normally holding the cutters separated, and vertically disposed guides that embrace the movable cutter holder. 11

3. A cutting machine comprising a stationary cutter holder and a movable cutter holder, each of which consists of a long rigid bar, cutters set in the meeting edges of said holders, levers provided with cams that bear against the upper edge of the movable cutter holder and exert downward pressure on same, a punch on one of said levers, and an inclined support for holding the work in 12 13

such a position that said punch will engage same.

4. A cutting machine comprising a stationary and a movable cutter holder, each of which consists of a long rigid bar, sharp-edged cutters set in the meeting edges of said holders, vertically disposed guides connected to the end portions of the stationary holder and embracing the movable holder, legs on the lower ends of said guides that hold said cutter holders in an upright position, levers pivotally connected to the upper ends of said guides and provided with cams that bear against the upper edge of the movable cutter holder, one of said levers having an operating handle, links pivotally connected to said levers for causing them to move in unison, a work table carried by the stationary cutter holder and projecting laterally from one side of same, a stop on one end of said work table, an inclined work support at one end of the machine, and a punch on one of said levers for forming a hole in the work mounted on said work support.

set in the meeting edges of said holders, vertically disposed guides connected to the end portions of the stationary holder and embracing the movable holder, legs on the lower ends of said guides that hold said cutter holders in an upright position, levers pivotally connected to the upper ends of said guides and provided with cams that bear against the upper edge of the movable cutter holder, one of said levers having an operating handle, links pivotally connected to said levers for causing them to move in unison, a work table carried by the stationary cutter holder and projecting laterally from one side of same, a stop on one end of said work table, an inclined work support at one end of the machine, and a punch on one of said levers for forming a hole in the work mounted on said work support.

In testimony whereof I hereunto affix my signature in the presence of two witnesses, this 30th day of April, 1914.

BENO J. GUNDLACH.
